UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAB ROOF

Application filed February 27, 1931. Serial No. 518,703.

This invention relates to car roofs of the type wherein the roof sheets form a continuous covering consisting of panels extending from side plate to side plate at one level, alternating with panels at a different level. Usually, in roofs of this type, the roof sheets are secured together by rivets that extend inside of the car, making the operation of riveting difficult and permitting water to leak into the car in case the rivet holes are not properly closed. The principal object of the present invention is to simplify the operation of riveting and to prevent water from entering the car through leaky rivet holes. Other objects are simplicity and cheapness of construction and compactness of design.

The invention consists principally in securing together the sheets of a roof of the above type by rivets located entirely outside of the car. It also consists in the construction, combinations and arrangements of parts hereinafter described and claimed.

In the accompanying drawing, which forms part of this specification and wherein like symbols refer to like parts wherever they occur,

Fig. 1 is a plan view of a portion of a car roof embodying my invention,

Fig. 2 is a vertical longitudinal cross-section through said roof on the line 2—2 in Fig. 1,

Fig. 3 is an enlarged vertical transverse cross-section through one-half of the car roof on the line 3—3 in Fig. 1,

Fig. 4 is a fragmentary plan view of the eaves portion of the car in the region of one of the seams,

Fig. 5 is a vertical cross-section on the line 5—5 in Fig. 4,

Fig. 6 is a vertical cross-section through one of the seams at the ridge, the section being taken on the line 6—6 in Fig. 1,

Fig. 7 is a side elevation of one of the eaves flashing members; and

Fig. 8 is a plan view of said flashing member.

Referring to the accompanying drawing, my invention is shown in connection with a car-roof the type wherein the metal roof sheets

1 are adapted, arranged and rigidly secured together along their adjacent side margins to form a self-sustaining, single-course roof consisting of alternating raised and depressed panels A and B, respectively, extending from side to side of the car. In the construction illustrated, the roof sheets are pitched or arched and span the space from side plate 2 to side plate 2 and have depending eaves flanges 3 that are riveted or otherwise secured to the vertical faces of such side plates. The side plates 2 are preferably of substantially Z-shaped cross-section with the inner flange upstanding and provided at its top with a flange 2a that extends inwardly at an angle conforming to the pitch of the lower panels A and serves to support the end portions of said panels.

Each roof sheet is offset along a longitudinal line, preferably near the medial line thereof, so that one-half of the body portion constitutes one of the upper panels A while the other half of said body portion constitutes one of the panels B. Each sheet is provided along the side edge of the lower panel B with an upstanding side marginal seam flange 4 which is bent inwardly at its top, as at 4a, so as to overhang the adjacent margin of said lower panel; and the other side of said sheet is provided with a relatively shallow depending flange 5 that extends along the outer edge of the upper panel A. The sheets are arranged on the car with the outer side marginal portion of the raised panel A of each sheet overlapping the laterally bent inwardly extending upper portion 4a of the upstanding seam flange 4 along the outer margin of the low panel B of the next sheet; and the overlapping marginal portion of said raised panel is secured to the inturned upper portion 4a of the upstanding flange 4 of the depressed panel B by means of rivets 5a. By this arrangement, sheets are secured together along their adjacent margins by rows of rivets that are located entirely outside of the car, where they are readily accessible for driving; and any water that gets into a leaky rivet hole will drip into the low panel and will drain lengthwise thereof and be discharged at the ends thereof outside of the car.

As shown in the drawing, the low panels B of the sheets rest on the inwardly projecting top flanges 2a of the side plates 2; and the high panels of said sheets are preferably pitched at the same inclination as the low panels from the ridge to points adjacent to the eaves where the high panels are pitched at a higher inclination than the low panels. The pitch of the laterally bent top portions 4a of the upstanding side flange 4 of the low panels B conforms to the pitch of the upper panels A; and said laterally projecting top portions 4a of the seam flanges 4 are removed where said flanges are turned with the body portions of the sheets to form the depending eaves flanges 3 thereof. The overlapping marginal portions of the upper panels of the sheet are bulged outwardly, as at 6, where they are turned down over the downturned side marginal flanges 4 of the lower panels; and the surplus metal resulting from the decreased depth of eaves portions of the sheets is utilized to increase the width of the overlapping marginal portion of the upper panel at the eaves.

In order to prevent water from being blown into the car through the ribs 6 that straddle the downturned end portions of the side marginal flanges 4 of the sheets, eaves flashing members 7 are secured to the sheet supporting top flanges 2a of the side plates beneath the upper panels of the roof sheets. Each of these eaves flashing members comprises a pan-shaped body portion that rests on and is riveted to the flange 2a of the side plate alongside of the flange 4 at the edge of the low panel. The eaves flashing is provided at its outer end with a flange 8 that extends downwardly between the side plate and the depending eaves flange 3 of the roof sheet.

The invention is not restricted to the forms and arrangements shown and described.

What I claim is:

1. A car roof comprising roof sheets adapted, arranged and secured together to form panels at one level alternating with the panels at a different level, adjacent sheets being connected by an upstanding flange along the side of the lower panel that is overlapped by the marginal portion of the adjacent upper panel and is provided at its top with a laterally projecting portion that overhangs said lower panel and is riveted flatwise to the underside of said marginal portion of said upper panel.

2. A car roof comprising roof sheets adapted, arranged and secured together to form panels at one level alternating with similar panels at a different level, adjacent sheets being connected by an upstanding flange along the side of the lower panel that is overlapped by the marginal portion of the adjacent upper panel and is provided at its top with a laterally projecting portion that overhangs said lower panel and is riveted flatwise to the

underside of said marginal portion of said upper panel, said upper panel having a depending flange along its side that overhangs the edge of the laterally bent upper portion of upstanding flange of said lower panel.

3. A car roof comprising roof sheets adapted, arranged and joined together to form panels at one level alternating with panels at a different level, the seam construction comprising an upstanding flange along the side edge of a lower panel that is bent inwardly at its top over said lower panel and is riveted flatwise to the underside of the margin of an adjacent upper panel.

4. A car roof comprising roof sheets adapted, arranged and secured together to form panels at one level alternating with panels at a different level, each sheet being provided along the margin of a lower panel with an upstanding flange that is bent inwardly at its top over said lower panel and riveted flatwise to the underside of the margin of an adjacent upper panel, the overlapping margin of said upper panel being bent downwardly over the edge of the laterally bent portion of the upstanding flange of said lower panel.

5. A car roof comprising roof sheets offset along longitudinal lines to form a panel at one level along one side of a sheet and a panel at a different level along the other side thereof, the side of a sheet having the low panel therein being flanged upwardly and thence inwardly over said low panel, said sheets being arranged with the marginal portion of the high panel of one sheet overlapping the upwardly and inwardly bent flange of the low panel of the next sheet and riveted thereto.

6. A car roof comprising roof sheets offset along longitudinal lines to form a panel at one level along one side of a sheet and a panel at a different level along the other side thereof, the side of a sheet having the low panel therein being flanged upwardly and thence inwardly over said low panel, said sheets being arranged with the marginal portion of the high panel of one sheet overlapping the upwardly and inwardly bent flange of the low panel of the next sheet and riveted thereto, the overlapping marginal portion of said high panel being bent downwardly over the edge of the inwardly bent portion of said low panel.

7. A car roof comprising roof sheets, each sheet being offset along a longitudinal line near the medial line thereof so that one-half of a sheet constitutes a panel at one level and the other half thereof constitutes a panel at a different level, the side marginal edge of the sheet having the low panel therein being provided with an upstanding flange that is bent inwardly at its top over said low panel, said sheets being arranged with the high panel of one sheet overlapping and riveted to the inwardly bent upper portion of

the upstanding flange of the low panel of the next sheet.

8. A car roof comprising roof sheets extending from side plate to side plate, said sheets being adapted, arranged and secured together to form panels at one level alternating with panels at a lower level, and members interposed between the end portions of the high panels and the side plates and rigidly secured to the latter.

9. A car roof comprising roof sheets extending from side plate to side plate with their ends turned down and rigidly secured thereto, said sheets being adapted, arranged and secured together to form panels at one level alternating with the panels at a different level, adjacent sheets being connected by an upstanding flange along the side of the lower panel that is overlapped by the marginal portion of the adjacent upper panel and is provided at its top with a laterally projecting portion that overhangs said lower panel and is riveted flatwise to the underside of said marginal portion of said upper panel, and members located beneath the upper panels near the adjacent upstanding flanges of the lower panels and rigidly secured to said side plates.

10. A car roof comprising roof sheets extending from side plate to side plate with their ends turned down and rigidly secured thereto, said sheets being adapted, arranged and secured together to form panels at one level alternating with the panels at a different level, adjacent sheets being connected by an upstanding flange along the side of the lower panel that is overlapped by the marginal portion of the adjacent upper panel and is provided at its top with a laterally projecting portion that overhangs said lower panel and is riveted flatwise to the underside of said marginal portion of said upper panel, members having pan-shaped body portions located beneath the upper panels near the adjacent upstanding flanges of the lower panels and rigidly secured to said side plates, and depending flanges extending between said side plates and the downturned ends of the roof sheets.

11. A car roof sheet offset vertically to form a panel at one level along one side of the sheet and a panel at another level along the other side of said sheet, said sheet having an upstanding side marginal flange along said lower panel that is bent inwardly at its top over said low panel.

12. A car roof sheet offset vertically to form a panel at one level along one side of the sheet and a panel at another level along the other side of said sheet, said sheet having an upstanding side marginal flange along said lower panel that is bent inwardly at its top over said low panel, and the side marginal edge having the high panel there-

13. A car roof sheet offset along a longitudinal line near the medial line thereof so that one-half of said sheet constitutes a panel at one level and the other half of said sheet constitutes a panel at a different level, the portion of the sheet having the low panel therein being flanged upwardly and thence inwardly over said low panel.

Signed at New Kensington, Pennsylvania, this 19th day of February, 1931.
